PLURAL SELECTIVE POSITION CAM
ACTUATOR FOR VALVES

Theodore N. Hannant, Cedar Grove, N. J., assignor to Specialties Development Corporation, Belleville, N. J., a corporation of New Jersey

Application November 9, 1949, Serial No. 126,375

12 Claims. (Cl. 74—107)

1

This invention relates to improvements in control devices, and is particularly directed to such devices which are adapted to be used for effecting the release of fluid pressure medium from containers.

While the fluid release control device of the present invention has manifold applications, it is particularly adapted for use with containers for fluid medium under pressure, such as carbon dioxide, employed for inflating rafts and the like.

Release control devices of the character indicated are employed for operating a valve to release medium from a container and generally comprise a pull cable wrapped about a sheave, which sheave when rotated by pulling on the cable, actuates the valve to effect the release of the medium. The housing of the device has a cable outlet with an opening disposed in the general direction of the cable, or in other words, in the direction of pull of the cable.

Inflatable rafts of the character with which the fluid release control devices of the present invention are suitable for use, are generally referred to as pack rafts, for the reason that they are each folded or packed in their deflated condition into a compact unit when not in use. One or more containers of fluid pressure medium are secured in the packed raft, each container having its discharge outlet leading to the interior of the raft, and each having a pull cable, one end of which is operatively connected to the release control device of the container and the other end of which extends to the outside of the packed unit, whereby, upon pulling the cable, the release control device is operated to effect the discharge of the fluid pressure medium into the raft to inflate the same. In such rafts, the direction of pull of the cable is predetermined by the position the container is to assume, within the packed unit, relative to the position or location of the outer end of the pull cable. In some rafts the pull is "downwardly," that is in a direction down along the body of the container, in which case a release control device having its cable outlet disposed in that direction is employed. Some such rafts employ more than one container which may be so disposed as to require release control devices operable by cables adapted to be pulled in different directions.

In securing the container and its release control device in the raft, it is important that the

2

proper release control device be employed, so that the pull will be direct, as distinguished from a pull which is indirect. Should a release control device having its cable outlet disposed in a "downwardly" direction be used where a pull in an "upwardly" direction is desired, a kink in the cable would result upon pulling the cable and thereby prevent ready operation of the release control device, resulting in failure to inflate the raft. For the foregoing reason, several types of release control devices have been supplied with containers for inflating rafts, each having its cable outlet in a fixed position, hence operable in one direction only, resulting in the necessity for a larger number of release control devices and containers to be on hand than is actually required.

Accordingly, one of the objects of the present invention is to provide a release control device of the character indicated which can be operated from a selected one of a plurality of positions.

Another object of the invention resides in the provision of a release control device of the character indicated which is so constructed that it will operate efficiently regardless of the selected position from which it is operated.

Another object is the provision of means for readily threading a cable about the sheave of the device.

A further object resides in the provision of means for indicating whether or not the fluid release mechanism has been operated.

A still further object of the present invention is the provision of a release control device which is readily convertible for operation from different directions.

Other and further objects of the present invention will be obvious from the following description and the accompanying drawings.

Generally, the fluid release control device of the present invention comprises a housing for attachment to a container of fluid medium under pressure and having a valve for controlling the release of the medium from the container. The housing provides a chamber which encloses the operating mechanism for the valve, which mechanism includes a plate having a cam secured to one face thereof, and an eccentrically disposed stud projecting from the other face thereof for mounting a sheave removably on the plate, and a cam follower adapted to be moved by the cam into engagement with the stem of the valve to effect the opening of the valve, whereby to permit the discharge of the medium into a raft with which the container is associated. A pull cable is provided for operating the sheave and has one of its

ends detachably connected to the sheave, so that when the other end of the cable is pulled the sheave will be rotated and the cable pulled free of the release control device, the rotation of the sheave effecting the rotation of the plate and cam. The housing has a pair of cable outlets disposed substantially opposite each other for selectively accommodating the cable in one of two selected positions. In order that the sheave may accommodate the pull cable, in either position selected, the sheave has a pair of apertures extending therethrough and disposed substantially 180° apart for the mounting the sheave in one of two selected positions on the aforesaid plate with the eccentric stud in either of the apertures. The sheave is provided with a cam face which normally is in register with the cable outlet after operation of the release control device, whereby to facilitate threading the cable about the sheave in conditioning the device for operation.

A preferred embodiment of a fluid release control device in accordance with the present invention is illustrated in the accompanying drawings wherein:

Figure 1 is a side elevational view of the release control device of the present invention, shown secured to a container for storing fluid medium under pressure.

Figure 2 is a longitudinal sectional view, partly in elevation, of the device as shown in Figure 1.

Figure 3 is a sectional view, partly in elevation, taken at right angles to the view shown in Figure 2.

Figure 4 is a view similar to Figure 1 with certain of the parts in different positions; and

Figure 5 is an exploded perspective view of the valve operating mechanism of the release control device.

Referring to the drawings in detail, a valve body 10 is provided with a connecting portion 12 internally threaded for attachment to the neck 14 of a container 16 for a fluid pressure medium, such as carbon dioxide.

The body 10 has a valve seat 18 formed therein on which a valve member 20 is normally held by means of a spring 22 when the container is empty, and which is held thereon by the pressure of the medium when the container is charged to form a closure for the outlet of the container. The valve member 20 has one end of a valve stem 24 secured thereto, the other end of which extends into a chamber 26. This stem serves as a closure opening or valve unseating member. The valve stem is adapted to operate in a bore 28 which is of larger diameter than the stem, the stem being provided with a collar 30 slidably fitting in the bore. A discharge outlet 32 communicates with the bore and is provided with a threaded nipple for the attachment of a connection (not shown) which leads to the interior of an inflatable raft (not shown).

A cam follower is disposed in the chamber 26 comprising an arm 34 pivotally mounted on the valve body by means of a screw threaded stud 36. The cam follower arm 34 has a roller 38 at its free end and is provided with a spring member 40 adapted normally to bias the arm away from the end of the valve stem and into engagement with a cam 42.

The cam 42 is carried on a plate 44 having a central bore for rotatably mounting the same on a shaft 48 secured to the valve body and extending into the chamber 26. The cam is permanently secured to the plate 44 in a fixed position thereon

by a stud or pin 46. The plate 44 has an eccentrically mounted stud 50 secured thereto, which stud projects from the face thereof opposite the cam face.

A sheave 52, as shown in Figure 5, has a central opening for mounting the same rotatably on the shaft 48, and has a pair of diametrically opposite apertures 54 and 56 on either side of the central opening, whereby the sheave may be mounted on the shaft 48 and the stud 50 in two different positions, as will be described more fully hereinafter. The sheave also has a transverse cut-out portion 58 providing a space between the periphery of the sheave and the inner wall of the chamber 26, the cut-out portion also providing a shoulder 60. The sheave also has a diagonal cut-away portion 62 adjacent the cut-out portion 58 which extends from one face of the sheave to the other at about an angle of 45° to the face of the sheave, providing a cam face, the purpose of which will be described presently. A peripheral other at about an angle of 45° to the faces of the sheave, one end of which terminates at the shoulder 60, and a short groove 66 is formed in the periphery of the sheave adjacent the shoulder. The sheave is held in place by a screw 53 screwed into the outer end of the central shaft 48.

As shown in Figure 2, the valve body is provided with an internally threaded pull cable outlet opening 68 for receiving a flexible conduit 70 having a coupling nut 72 thereon exteriorly threaded for threading into the opening 68. The cable outlet 68 communicates with the chamber 26 and is adapted to receive a flexible cable 74 loosely threaded through the flexible conduit and having a ball 76 and an integral guide piece or handle 78 carried on its inner end, the said ball 76 providing anchoring means for detachably connecting that end of the cable to the sheave at the cut-out 58 and in engagement with the shoulder 60 of the sheave. The other end of the pull cable has a clip 79, which may be attached to a handle (not shown) at the outside of the packed raft, or to an extension cable (not shown) extending to the outside of the packed raft.

The valve body 10 is provided with another internally threaded pull cable outlet 80 similar to the outlet 68 and disposed substantially opposite the latter outlet. The outlet 80 normally is blocked, as shown in Figure 2, by a removable stud 82 having a bevelled face and being held in place by a threaded plug 84. This stud and the flexible conduit are interchangeable, whereby the cable may extend out of the valve body in either direction, as will be more fully described hereinafter. A split spring obturating ring 85 is disposed in a groove formed on the inner wall of the chamber 26, the purpose of which will be described presently.

The chamber 26 has an open end which is normally closed by a cover plate 86 having a flange 88 and held in place by screws 90.

In assembling the fluid release device of the present invention, the cam follower arm 34 is secured in the bottom wall of the chamber 26 by means of the screw threaded stud 36 on which the arm is pivotally mounted, and at the same time the spring 40 is inserted in place. The plate 44 carrying the cam 42 is then set in position on the shaft 48 with the cam follower roller 38 in engagement with the cam and with the stud 50 on the plate 44 projecting outwardly of the chamber. The sheave 52 is then placed on the shaft 48 and superimposed on the plate with the

stud 50 in one of the apertures 54 or 56 of the sheave, depending upon which cable outlet is to be utilized, as will be described presently, after which the retaining screw 53 for the sheave is secured in place. The obturating ring 85 is then set in its groove, and the pull cable inserted through the flexible conduit, whereby the ball 76 is in engagement with the shoulder 60 of the sheave 52 and with the portion of the cable adjacent the ball in the short groove 66 and the cable wrapped about the sheave.

Assuming that the valve assembly of the present invention is to be operated by the pull cable arranged in the position shown in Figure 1, the sheave 52 will be in the position shown in Figures 2 and 3 with the stud 50 in the aperture 56. Should it be desired to convert the release device whereby to reverse the direction of pull, the flexible conduit 70 and its nut 72 are removed from the position shown in Figure 1, the blocking plug 84 and the blocking stud 82 are removed from the cable outlet 88 and transferred to the cable outlet 68, and the flexible conduit is secured in the cable outlet 89, as shown in Figure 4. The sheave 52 is then removed from the shaft 48 and the stud 50 is turned around about 180 degrees and replaced with the stud 50 entering the aperture 54 in the sheave, after which the retaining screw is replaced to hold the sheave in its new position.

In threading the cable about the sheave 52, the cable is pushed through the flexible conduit with its ball and guide piece leading. If the sheave is in proper position for threading of the cable through the selected cable outlet, the cam face provided by the 45 degree cut-away portion 62 of the sheave will be in register with the cable outlet, so that the guide piece and the ball will engage the cam face, and will be guided thereby toward the open end of the chamber 26, whereby it can readily be grasped by hand and wrapped about the sheave with the ball positioned in engagement with the shoulder 60 of the sheave. The cover plate 86 may then be placed in position to cover the open end of the chamber 26.

The portion of the ring 85 adjacent the cable outlet prevents the threading of the cable about the sheave, except when the sheave is in the proper position to receive the cable through that outlet, the proper position being determined by the cam face 62 of the sheave being in alignment with the cable outlet.

The outer end of the stud 50 is preferably colored, green for example, and the outer face of the sheave 52 is of a distinctive color, red for example. The cover plate has a window 92 therein with which the stud 50 is in register when the valve is closed, so that there is a visible indication of the position of the valve. In other words, when the stud, or the green color of the stud end, is seen through the window it will be an indication that the valve is closed. However, when the valve has been operated, the stud is no longer in register with the window, because of the rotation of the sheave, and the red color of the outer face of the sheave is visible through the window thereby indicating that the valve has been operated and is open.

In use, the container 16, with its valve assembly 10, is attached to a pack raft, in its deflated condition, with the discharge outlet 32 of the release control device in communication with the interior of the raft. The clasp 79 at the outer end of the cable is attached to a handle at the outside of the packed raft, or to an ex-

tension cable having a handle disposed at the outside of the raft when in folded condition. When the cable is pulled, the sheave will be rotated to effect the rotation of the plate 44 and the cam 42 carried thereby. The cam engages the cam follower roller 38 causing the cam follower arm 34 to engage the stem 24 of the valve 20, thereby moving the same off its seat 18 and effecting the discharge of the pressure medium from the container into the raft to inflate the same. As will be understood from the foregoing, the cable will be completely pulled out of the valve assembly which serves as an additional indication that the release control device has been operated.

In some rafts, wherein more than one container of fluid pressure medium is employed, the outer end of the pull cable of the release control device of one container is attached to a portion of the raft which is first inflated upon the discharge of the other container, so that the said cable is pulled automatically by the raft itself upon its initial inflation. The present invention, obviously, is suitable for use with such rafts.

From the foregoing, it will be seen that the present invention provides a fluid release control device for a container of fluid pressure medium capable of being mounted on an inflatable raft, whereby the device can be readily converted for operation from a plurality of positions, which device will operate efficiently regardless of the position from which it is operated.

It will also be seen that visual indicating means are provided whereby it can readily be determined whether or not the valve has been opened and the contents of the container discharged.

From the foregoing description, and the accompanying drawings, it will also be seen that the valve assembly of the present invention includes a sheave having means to facilitate threading of the cable about the sheave.

Likewise, it will be seen that the operation of the valve by engagement of the valve stem by a pivoted cam follower results in a more efficient operable device than where the cam itself engages a valve stem.

While I have illustrated and described a preferred embodiment of my invention, it is to be understood that I do not wish to be limited to that precise structure and arrangement of parts, as obviously various changes and modifications may be made therein without departing from the spirit and scope of my invention.

I claim:

1. In a fluid release control device for effecting movement of a closure opening member, the combination of a housing; a pull cable; a rotatable member mounted within the housing and having means for connecting the pull cable thereto; a cam for operating the closure opening member; and means for operatively connecting the rotatable member to the cam in one of a plurality of relative positions, said housing having a plurality of spaced apertures for selectively accommodating the pull cable, the selected aperture being determined by the position of the rotatable member relative to the cam.

2. In a fluid release control device for effecting movement of a closure opening member, the combination of a housing; a pull cable; a rotatable member mounted within the housing and having means for detachably connecting one end of the pull cable thereto; a cam for operating the closure opening member; and means for oper-

atively connecting the rotatable member to the cam in a selected one of two relative positions, said housing having a pair of substantially oppositely disposed apertures for selectively accommodating the pull cable, the selected aperture being determined by the selected position of the rotatable member relative to the cam.

3. In a fluid release control device for effecting movement of a closure opening member, the combination of a housing; a pull cable; a rotatable member mounted within the housing and having means for detachably connecting one end of the pull cable thereto; a cam for operating the closure opening member; means for operatively connecting the rotatable member to the cam in a selected one of two relative positions, said housing having a pair of substantially oppositely disposed apertures for selectively accommodating the pull cable, the selected aperture being determined by the selected position of the 15 rotatable member relative to the cam, and means in said housing preventing the connection of the cable to the rotatable member unless inserted in the selected aperture.

4. In a fluid release control device for effecting movement of a closure opening member, the combination of a housing; a pull cable; a rotatable member mounted within the housing and having means for detachably connecting one end of the pull cable thereto; a cam for operating the closure opening member; means for operatively connecting the rotatable member to the cam in one of two relative positions, said housing having a pair of substantially oppositely disposed apertures for selectively accommodating the pull cable, the selected aperture being determined by the position of the rotatable member relative to the cam, and a flexible conduit for the cable having means for attachment of one end of the conduit in a selected aperture.

5. In a fluid release control device for effecting movement of a closure opening member, the combination of a housing; a pull cable; a rotatable member mounted within the housing and having means for detachably connecting one end of the pull cable thereto; a cam for operating the closure opening member; means for operatively connecting the rotatable member to the cam in one of two relative positions, said housing having a pair of substantially oppositely disposed screw threaded apertures for selectively accommodating the pull cable, the selected aperture being determined by the position of the rotatable member relative to the cam, a flexible conduit for the cable having screw threaded means for attachment of one end of the conduit in a selected aperture, and means for closing the other of said apertures.

6. In a fluid release control device for effecting movement of a closure opening member, the combination of a housing; a pull cable; a sheave mounted within the housing and having means for detachably connecting one end of the pull cable thereto; cam means for effecting operation of the closure opening member; and a stud associated with said cam means; said sheave having a pair of apertures disposed substantially 180 degrees apart adapted to receive said stud, whereby to operatively connect the sheave to the cam in one of two selected positions relative to the cam; said housing having a pair of substantially oppositely disposed apertures for selectively accommodating the pull cable, the selected aperture being determined by the selected position of the sheave relative to the cam.

7. In a fluid release control device for effecting movement of a closure opening member, the combination of a housing; a pull cable; a sheave mounted within the housing and having means for detachably connecting one end of the pull cable thereto; a cam for effecting operation of the closure opening member; a plate disposed between the sheave and cam on one side of which the cam is mounted; and a stud carried by said plate on the side thereof opposite the cam; said sheave having a pair of apertures disposed substantially 180 degrees apart adapted to selectively receive said stud, whereby to operatively connect the sheave to the plate and cam in one of two selected positions relative to the cam; said housing having a pair of substantially oppositely disposed apertures for selectively accommodating the pull cable, the selected aperture being determined by the selected position of the sheave relative to the cam.

8. In a fluid release control device for effecting movement of a closure opening member, the combination of a housing providing a chamber; a pull cable; a shaft in said chamber; a sheave 25 rotatably mounted on said shaft and having means for detachably connecting one end of the pull cable thereto; a cam rotatably mounted on said shaft for effecting operation of the closure opening member; a plate rotatably mounted on said shaft and disposed between the sheave and cam on one side of which the cam is mounted; a stud carried by said plate on the side thereof opposite the cam; said sheave having a pair of apertures disposed substantially 180 degrees apart adapted to selectively receive said stud, whereby to operatively connect the sheave to the plate and cam in one of two selected positions relative to the cam; and means for securing said sheave in its selected position; said housing 30 having a pair of substantially oppositely disposed apertures for selectively accommodating the pull cable, the selected aperture being determined by the selected position of the sheave relative to the cam.

9. A fluid release control device for effecting movement of a closure opening member comprising in combination, a housing, a sheave rotatably mounted in the housing, a pull cable adapted to be wrapped about said sheave and having anchor means on one end thereof, said housing having an aperture formed therein through which the pull cable extends, means formed on the sheave for detachably connecting the anchor means of the cable to the sheave, means associated with and operable by the sheave for effecting movement of the closure opening member upon pulling the cable, and guide means on said sheave for guiding the anchor means to facilitate wrapping of the cable about the sheave.

10. A fluid release control device for effecting movement of a closure opening member comprising in combination, a housing having a chamber provided with an open end; a cover for said open end; a sheave rotatably mounted in said chamber; a pull cable adapted to be wrapped about said sheave and having anchor means on one end thereof; said housing having an aperture formed therein through which the pull cable extends; means formed on the sheave for detachably connecting the anchor means of the cable to the sheave; cam means associated with and operable by the sheave for effecting movement of the closure opening member upon pulling the cable, and guide means formed on one face of the sheave in alignment with said aperture for

guiding the anchor means outwardly of said open end to facilitate grasping the cable and wrapping the same about the sheave.

11. A fluid release control device for effecting movement of a closure opening member comprising in combination, a housing having an open end, rotatable sheave means removably mounted in the housing, a pull cable adapted to be wrapped about said sheave and having anchor means on one end thereof, said housing having an aperture formed therein through which the pull cable extends, shoulder means formed on the sheave for detachably connecting the anchor means of the cable to the sheave, means associated with and operable by the sheave for effecting movement of the closure opening member upon pulling the cable, and bevelled guide means formed in one face of said sheave adjacent said shoulder means for guiding the anchor means outwardly of the open end of the housing to facilitate gripping the cable and wrapping the same about the sheave with the anchor means in engagement with said shoulder.

12. A fluid release control device for effecting movement of a closure opening member comprising in combination, a housing having an open end, rotatable sheave means removably mounted in

the housing, a pull cable adapted to be wrapped about said sheave and having anchor means on one end thereof, said housing having an aperture formed therein through which the pull cable extends, shoulder means formed on the sheave for detachably connecting the anchor means of the cable to the sheave, means associated with and operable by the sheave for effecting movement of the closure opening member upon pulling the cable, and a cover plate for said open end having a window disposed in a predetermined position therein; said sheave means being provided with two distinctive indicia means, one of which is visible through said window when the release device has not been operated and the other being visible through the window when the device has been operated.
